Glossary

UNITED STATES PATENT OFFICE.

WILLIAM T. LONG, OF SUMNER, WASHINGTON, ASSIGNOR OF ONE-HALF TO
HENRY KNOBLAUCH, OF SUMNER, WASHINGTON.

TRAIN-ORDER DELIVERING AND RECEIVING APPARATUS.

No. 857,641.

Specification of Letters Patent.

Patented June 25, 1907.

Application filed April 9, 1907. Serial No. 367,214.

To all whom it may concern:

Be it known that I, WILLIAM T. LONG, a citizen of the United States of America, residing at Sumner, in the county of Pierce and State of Washington, have invented certain new and useful Improvements in Train-Order Delivering and Receiving Apparatus, of which the following is a specification, reference being had therein to the accompanying drawing.

This invention relates to devices and apparatus for the delivery of written train orders to a locomotive engineer and to the train conductor while the train is in full motion, and has for its object to provide means on the train and at a station to exchange carrier bodies in which the written train order is fastened, to provide a night signal whereby an approaching train may know if it is to receive orders at the station, and to so construct the apparatus on the train as to be reversible and adapted to be used when the train is moving in either direction. I attain these objects by the devices and mechanism illustrated in the accompanying drawings, in which,

Figure 1 is a side view of a portion of a locomotive cab equipped with my invention set for delivering and receiving a carrier, Fig. 2 is an end view showing a stationary apparatus being approached by an apparatus mounted on a locomotive cab, and Fig. 3 is a plan thereof. Fig. 4 is a plan of a portion of the mechanisms showing a carrier on the locomotive in the act of being caught by the stationary apparatus, while the moving apparatus is set to catch the stationary carrier in which the written orders are fastened, and Fig. 5 is a similar view showing the carriers exchanged, the receiving mechanism on the locomotive being in the act of closing on the caught carrier. Fig. 6 is a plan of the carrier, showing the order box thereon, Fig. 7 is a side view thereof, and Fig. 8 is a section on the line 8—8 in Fig. 7.

Similar numerals of reference refer to similar parts throughout the several views.

The station apparatus will be located at each telegraph station on the road, and consists of a post 1 placed about eight feet from the rails and being about ten feet high. The post 1 carries the receiving and delivering apparatus for both the engineer's orders and the conductor's orders, the one being placed

below the other. The posts must be placed 55 uniformly relatively to the rails both as regards horizontal and vertical distance therefrom and the apparatus mounted thereon must also be uniform in all stations. Further, the apparatus on all the trains must be 60 at the same heights above the rail as the stationary apparatus, the engineer's apparatus at one height and the conductor's apparatus at the other height, and they must be so adjusted that when they are placed in their operating positions they will come within operative distance of the stationary apparatus respectively.

The two apparatus on the post 1 are similar in all respects, one being below the other, 70 and are linked together by the rod 2 so that when the upper one is raised into operative position the lower one is similarly raised. Both the apparatus are pivoted to the two similar brackets 3 secured to the post 1. A 75 lever 4 is pivoted above the top of the post 1, and has one end connected by a bar 5 to the arm 6 which is journaled to the rear of the post at a convenient height thereon and which has a handle 7 secured thereto whereby the parts are operated. The other end of the lever 4 is connected by a link 8 to the upper apparatus and by the link 2, as above described, to the lower apparatus, in such manner that when the handle 7 is brought into 85 the position shown in Fig. 2 the apparatus will extend out horizontally from the two brackets 3. The stationary apparatus is preferably made double so as to be ready for trains in either direction. The two castings 90 9 are pivoted to the brackets 3 and are connected together by the rod 10; the center of which the links 2 and 8 also loosely engage. To the outer sides of the castings 9 are fastened the bent iron pieces 11 which first pass 95 toward the center and then bend out to form the catching point, and then turn toward each other, parallel with the track, and join between the plates of the delivering apparatus. To the castings 9 are pivoted the closing pieces formed with an actuating leg 12 extending across the receiving space of the bent iron piece 11, and with a locking leg 13 at right angles to the leg 12 and adapted to be brought into touch with the catching point 105 of the piece 11 after the carrier has been caught, to prevent it from rebounding and falling off therefrom. This closing piece is

acuated by means of a spring 14 engaging between the casting 9 and a strap 15 mounted on the bar 10 and pivoted to the closing piece in such manner that the pivots are just beyond their dead centers when the receiving mechanism is set for action but as soon as the leg 12 is moved by coming in contact with the moving carrier 16, held by the delivering apparatus on the locomotive (Fig. 4), the spring 14 acts to close the leg 13 against the catching point (Fig. 5). A pin 17 keeps the closing piece from opening so far that the force of the blow delivered by the carrier 16 will not turn it, and the pin 18 near the end of the leg 13 engages with the piece 11 near the point and keeps the closing piece from turning unnecessarily far. The delivering apparatus is mounted between the plates 19 and consists of two levers 20 pivoted to the plates 19 and oppositely shaped and adapted to engage the two slots 21 made in one side of the carrier 22 to hold the carrier 22 so that it will extend out vertically from the stationary apparatus on the locomotive or car. The outer ends of the levers 20 are kept pressed toward each other by the pressure of the spring 23 fitted between their other ends.

The apparatus on the train is similar to the above described stationary apparatus, but is slightly different in form on account of the circumstances under which it is operated. A bracket 24 is secured to the car or locomotive at the proper height above the rail so that when the apparatus extends horizontally therefrom it will be in operative position with regard to the upper or lower stationary apparatus, as the case may be. A second bracket 25 is journaled in this bracket 24 and is secured to the horizontal bar 26 extending to the nearest opening, where a handle 27 is attached to swing the apparatus to the horizontal position. Normally, the bracket 25 is swung up or down to fold the apparatus against the sides of the cab or car. A pivot 28 extends out from the bracket 25, and is journaled therein, and has a retaining spring 29 secured thereto and adapted to engage under the lugs 30 on the bracket 25. Lower lugs 31 are provided to keep the spring 29 from turning too far. This pivot is used to reverse the apparatus so that it may be used when the train is passing in either direction. The block 32 is secured to the pivot 28 and carries the apparatus and corresponds with the castings 9. The bar 33 extends from the block 32 and corresponds with the bar 10. The bent iron piece 34 is secured to the block 32 and to the bar 33 and is shaped similarly to, and corresponds with, the bent iron piece 11. The closing piece is pivoted to the block 32 and has legs 35 and 36 similarly shaped and corresponding with the legs 12 and 13. The spring 37, the strap 38, and the pins 39 and 40 correspond to the similar

parts 14, 15, 17 and 18 respectively. The delivery apparatus consists of a flat spring 41 secured to the catching point 34 near the point thereof, being open or free at its rear end. The spring 41 engages in one of the transverse slots 42 in the carrier pressing the carrier against the bent iron piece 34 which enters the other slot. The two parts 34 and 41 hold the carrier so that it extends outward from the apparatus and is in vertical position and adapted to pass over the catching point 11 of the stationary apparatus.

In Figs. 6 and 7 is shown the carrier box into which the written orders are placed. This consists of a box 43 to which is pivoted at one end the lid 44. The other end of the lid enters under an overhanging lug 45 of the box, and has a lug 46 on its side. The lid is opened by turning it horizontally on its pivot so that its end is removed from under the lug 45 and until it is opened sufficiently to insert or remove the order. A spring may be placed in the box to keep the lid normally closed. The carriers are annular and are preferably made rectangular as shown in the drawings, though other shapes may be used if desired.

In order that the train crew may know that orders await them at a station, I mount a lamp 47 on the top of the post 1, adjacent to the lever 4 and secure a shade 48 to the side of the lever 4. The lamp has a metal body with holes in its sides and the parts are so arranged that when the mechanism is set for the exchange of carriers the shade 48 is withdrawn from the holes in the lamp, but when the mechanism is lowered the shade 48 covers the holes in the lamp, rendering the light invisible.

Having described my invention, what I claim is:

1. In a train order delivering and receiving apparatus, the combination of an annular carrier adapted to contain the train order, spring actuated means adapted to releasably hold said carrier, and a catching point moving relatively to said carrier and adapted to enter said carrier and remove it from said holding means.
2. In a train order delivering and receiving apparatus, the combination of an annular carrier adapted to contain the train order, spring actuated means adapted to releasably hold said carrier, a catching point moving relatively to said carrier and adapted to enter said carrier and remove it from said holding means, and a spring actuated closing piece pivoted to the catching mechanism and adapted to prevent said carrier from falling therefrom.
3. In a train order delivering and receiving apparatus, the combination of a supporting body, spring actuated holding means adapted to releasably hold a carrier and pivoted to said supporting body, means mounted on the supporting body and engaging said spring

- actuated holding means to control it on its pivot, an annular carrier adapted to contain the train order and to be held by said spring actuated holding means, a second supporting body moving relatively to said first supporting body, a catching point pivoted to said second body and adapted to enter said carrier and remove it from said holding means, means engaging said catching point to control it on its pivot, and a spring actuated closing piece pivoted to the catching mechanism and adapted to prevent said carrier from falling therefrom.
4. A train-order carrier comprising an annular body having a portion of its sides cut away to form two opposite slots adapted to be engaged by a carrier holder.
5. In a train-order delivering apparatus, the combination of an annular carrier, a receptacle mounted thereon, opposite slots formed in the sides of said carrier, and a spring actuated holding means whereby said carrier is releasably held in operative position.
- 25 6. In a train-order receiving apparatus, the combination of an annular carrier moving relatively to the receiving apparatus and having a receptacle mounted thereon, a catching point adapted to enter said annular carrier and to receive it thereon, and a spring

actuated closing piece adapted to be engaged and started by said annular carrier and to close behind said carrier to prevent it falling from said catching point.

7. In a train-order receiving apparatus, 35 the combination of a receiving body having a catching point extending therefrom and adapted to enter an annular carrier, a closing piece pivoted to said receiving body and having one leg extending toward the catching 40 point and adapted to be engaged by and moved by the annular carrier and having a second leg withdrawn from said catching point when the mechanism is set to receive a carrier but engaging said catching point behind said carrier when it has moved said first leg, and a spring actuated link secured to said closing piece and adapted to hold said second leg in its withdrawn position when the mechanism is set to receive a carrier and to 45 swing said closing piece so that said second leg will engage said catching point when said carrier has moved said first leg.

In testimony whereof I affix my signature in presence of two witnesses.

WILLIAM T. LONG.
